UNITED STATES PATENT OFFICE.

GEORGE D. HAWORTH, OF DECATUR, ILLINOIS.

SEED-PLANTER.

SPECIFICATION forming part of Letters Patent No. 402,669, dated May 7, 1889.

Application filed September 29, 1888. Serial No. 286,718. (No model.)

To all whom it may concern:

Be it known that I, GEORGE D. HAWORTH, of the city of Decatur, county of Macon, and State of Illinois, have invented certain new and useful Improvements in Seed-Planters, of which the following is a specification.

My invention relates, first, to mechanism for drilling the seed; second, to a device for regulating the depth of the cut of the runners; third, to a lock to hold the runners in the ground, and, fourth, to a detachable device for marking the ground to guide the driver.

In the drawings accompanying and forming a part of this specification, Figure 1 is a side elevation of a corn-planter embodying my invention. Fig. 2 is a plan of the drill mechanism. Fig. 3 is a front elevation of the same. Fig. 4 is a vertical section of the rotating head of the drill mechanism. Fig. 5 is a plan of a side of a planter with a marker attached thereto. Fig. 6 is a perspective view of the device used to regulate the depth of the cut of the runners. Figs. 7 and 8 show details in the connection of the marker-bar. Fig. 9 is a perspective view of the principal element in the device for regulating the depth of cut of the runners. Fig. 10 is a face view of the head shown in Fig. 4, taken from the right side of said figure; and Fig. 11 is an elevation of the same device, taken from the opposite side.

A sprocket-wheel (indicated by reference-letter *a* in Fig. 1) is secured to a planter-wheel in a position concentric therewith. A sprocket-chain, *b*, connects wheel *a* with sprocket-pinion *c* of the drill mechanism and conveys motion from the planter-wheel thereto. Arm *d* pivots loosely in line with the axle of the planter and carries roller *e*, that bears on chain *b* in a manner to take up slack. The shaft *g* (seen in Figs. 2 and 3) carries pinion *c* and rotates therewith. The head *h* ordinarily rotates with shaft *g*, on which, however, it is loosely mounted, as will hereinafter appear, and it has a bearing, *n'*, for the L-lever, that conveys motion to the seed-slide of the planter. The L-lever comprises the arm *p*, that pivots on vertical stud *q* and has a termination, *s*, to actuate the seed-slide, and arm *o*, that is actuated by the head and

has forks *o' o''*, that pivot on arm *p*. The seed-slide *u* has a slotted bracket, *t*, in which the termination of arm *p* operates. The arm *p* has an end projection at *r* to form a bearing for fork *o'* and has a pivot at *r'* in line with *r*, that forms a bearing for fork *o''*. The stud *q* is supported by bracket *x*. The shaft *g* has bearings in bracket *w*. Both brackets are secured to a cross-bar, *v*, of the planter-frame. The rotation of head *k l* is imparted to the end of arm *o*, the forks rock on arm *p* and impart oscillating motion thereto, the end *s*, working loosely in the slot of bracket *t*, imparts rectilinear reciprocating motion to the seed-slide *u*, and the seed is dropped at short and regular intervals. This is the operation in detail. Briefly expressed, the L-lever acts as a pitman in conveying the rotary motion of the head to the reciprocating seed-slide.

The head is composed of two plates, *k* and *l*. The first, as may be seen in Fig. 4, is slotted at *k'''* and has a hole for bolt *m*. It also has a collar, *k'*, and a boss, *k''*, with grooves in its face. The second plate, *l*, is slotted narrowly at *l'* to receive bolt *m* and more widely at *l''* to receive boss *k''*. It projects laterally at *n* into slot *k'''*, and its projection has perforation *n'* to receive the end of arm *o*. This construction, with the exception of the collar and boss on the inner plate, is to permit the length of the stroke of the seed-slide to be regulated, the requisite operation consisting simply in loosening bolt *m*, moving projection *n* nearer to or farther from the shaft, and retightening the bolt.

A slide, *h*, engages the collar of plate *k*. It has longitudinal motion on the shaft, and it is provided with ledges *i* and tooth *i'*. (Seen in Fig. 3.) A lever, *f*, fulcrumed over the slide, has projections *f'* and *f''* extended beyond the fulcrum in nearly-opposite directions. When the lever is thrown in one direction, a projection striking against the tooth carries the slide, and with it the head, along the shaft. When the lever is thrown in the opposite direction, the opposite projection strikes the tooth and returns the sleeve and head to their original positions. This operation, which may be easily effected by the driver with his foot, enables the slots of the

boss to be made to engage or disengage pins *g*' of the shaft, and so cause the head to operate or not, as may be desired.

In Fig. 5, 15 is the marker, 16 the marker-bar, 17 a line connecting the marker with the eye of hook 18, and 19 is a line extending from the bow of the hook to the driver on his seat. The washer 20 is secured to the end of the planter-axle and has the elongated

knob 21, as shown in Fig. 8. The bar 16 has a casting, 22, that is slotted in the direction of the length of the bar at 23. A whiffle-tree is shown at 24 and a planter-wheel at 25. The marker-bar is attached by placing the casting in line with the knob, slipping it over the same, swinging the bar to the position shown, and catching the hook in the whiffle-tree-ring or other convenient point of connection.

20 When the end of the field is nearly approached, the driver pulls line 19, detaching the hook from the ring, and draws the marker forward until the bar is in line with the direction of the motion of the planter, when 25 the slot will slip over the knob, and the bar will thus be detached from the planter. After the team has been turned around the marker may be replaced on the opposite side of the planter in the manner heretofore specified.

30 In Fig. 6, 10 represents a slotted bracket permanently secured to the axle of the planter. 11 represents a slotted bracket permanently secured to the frame carrying the dropping mechanism, and 26 represents a bolt connecting the brackets in a manner permitting free vertical motion. Secured to the axle in a manner permitting vertical adjustment is bracket 12. (Seen clearly in Fig. 9.) This 40 bracket has projection 13, that extends between the permanent brackets under the bolt and limits the downward motion of the planting mechanism and the depth of the cut of the runners.

45 The extent of the slots in the permanent brackets limits the extreme adjustment of the planting mechanism. The adjustable bracket is used to limit the depth of penetration of the runners to suit various conditions of soil, 50 season, &c., it being desirable to plant deeper at times and under some conditions and shallower at other times and under other conditions. The adjustable bracket has a longitudinal slot, 14, through which the securing-bolt passes; but other well-known means may be employed to give the necessary adjustment.

55 In Fig. 1 reference-numeral 1 designates the hand-lever used to raise and lower the 60 planting mechanism. 2 is the seat-supporting bar, provided with staple 3. 4 is a lock-bar swinging pendent from a pivot on lever 1 and having teeth 5 and 6, adapted to staple 3. The rod 7 is used to connect lever 1 with 65 treadles. (Not seen.) Rod 8 connects lever 1 with the planting mechanism. 9 is the

standard on which lever 1 pivots. The lock-bar is curved or forwardly inclined, and is swung in such position that the lever may be raised and lowered without the teeth engaging the staple. This enables the driver to regulate the depth of cut of the runners above a certain limit by pressure of his feet on the treadle. When it is desirable to cut at a uniform depth, the lock-bar is swung back of the 75 staple and a tooth is caught therein.

I claim—

1. In drill mechanism for seed-planters, in combination, a rotating head and an L-lever having one arm pivoted on the other and connected the one arm with the head and the other arm with the seed-slide of the planter, as and for the purpose set forth.

2. In drill mechanism for seed-planters, in combination, a rotating head having a bearing for a lever adjustable with relation to the center of rotation, and an L-lever pitman connected at one end with the bearing of the head and at the other end with the seed-slide of the planter, as and for the purpose 90 set forth.

3. In drill mechanism for seed-planters, in combination, a shaft, a head on the shaft, an L-lever having one arm pivoted on the other and connected the one arm with the head and 95 the other arm with the seed-slide of the planter, and sprocket-gearing connecting the shaft with a wheel of the planter, as and for the purpose set forth.

4. In combination, the shaft having the laterally-projecting pins, the head adapted to move longitudinally on the shaft and having slots to engage the pins, a lever to move the head with relation to the pins, and an L-lever pitman connecting the head with the seed-slide of the planter, as and for the purpose 100 set forth.

5. In combination, the shaft having the pins, the head movable on the shaft and having slots to engage the pins, the slide engaging the head and having the tooth, the lever having the projections adapted to strike the tooth of the slide, and the L-lever pitman connecting the head with the seed-slide of the planter, as and for the purpose 105 set forth.

6. In combination with slotted bracket 10, secured to the wheel-frame of the planter, slotted bracket 11, secured to the planting mechanism, and bolt 26, extended through the slots of the brackets, adjustable bracket 12, having projection 13 extended under bolt 26, as and for the purpose set forth.

7. In combination, lever 1, fulcrumed on the frame, supported by the wheels, and connected with the planting mechanism, bar 2, 125 having catch projection 3, and lock-bar 4, adapted to pass ordinarily with its back to the catch, and having teeth on its face to engage the catch, as and for the purpose set forth.

8. In combination, washer 20 on the wheel-hub, having knob 21, marker-bar 16, having

the oblong slot adapted to the knob, the marker, the hook 18, the line 17, connecting the marker with the eye of the hook, and line 19, connected with the bow of the hook, as 5 and for the purpose set forth.

9. In combination with a marker for planters, a hook having an ordinary eye to connect with a brace-line, and also having a connec-

tion in the bow for a detaching-line, as and for the purpose set forth.

In testimony whereof I sign my name in the presence of two subscribing witnesses.
